(57) **CLAIM**

The ornamental design for an attachment for paint pot as shown and described.

DESCRIPTION

FIG. 1 is a perspective view showing the front, top and right sides of the attachment for paint pot;

FIG. 2 is a perspective view showing the rear, top, and left sides thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a left side elevation view thereof;

FIG. 8 is a right side elevation view thereof;

FIG. 9 is a perspective view showing the front, bottom, and left sides thereof;

FIG. 10 is a perspective view showing the rear, bottom, and right sides thereof;

FIG. 11 is a front environmental view of the attachment for paint pot attached to a paint pot; and,

FIG. 12 is a rear environmental view of the attachment for paint pot attached to a paint pot.

The broken lines illustrating the paint pot form no part of the claimed design.

1 Claim, 11 Drawing Sheets
